TRIMMING AND PINKING DEVICE AND
THE LIKE

Nellie C. Smith, Santa Barbara, Calif.

Application April 26, 1943, Serial No. 484,665

4 Claims. (Cl. 112—124)

My invention relates to edge cutting devices and more particularly to such apparatus, which are especially adapted for trimming and for finishing the seamed edges of cloth or other suitable materials, and which also is to be used for cutting said materials in a straight line, or, if so desired for cutting same in a scalloping form which is generally called pinking, and which when in such use, is to be employed for the purpose of preventing the raveling of the cloth edges, and thereby preventing said seamed edges from becoming weakened and also for giving said edges a finished appearance when completed.

Manifestly an object of my invention is to provide a suitable pinking device which may be attached to and disposed upon the mounting plate, which is positioned upon the base member of a sewing machine, regardless of its make, said device to be disposed at a close proximity to the feed member bar and the needle bar thereof, and which in operation will pink the cloth edges while simultaneously sewing together said edges of said material.

Accordingly an object of my invention is to provide a suitable pinking device which, in its preferred construction, consists of a horizontally disposed plate means, the top surface section of which is provided with circularly disposed scalloping cutting edges over which a suitable roller means is placed and which is held thereover at a suitable pressure, while at the underside of said plate means a suitable mounting plate is positioned, the upper surface section of which is provided with a circular groove, wherein a set or a row of frictionless bearing balls are placed, said circular plate means being then disposed upon said row of frictionless ball bearings, having at its center a suitable stem means which is disposed within a suitable center bushing means adapted for holding said stem means in place and for engaging a suitable friction drive means which is provided with a suitable extension lever which extends outwardly therefrom, for engaging and for transmitting the reciprocal action of the feed bar member of the sewing machine into a horizontally pivotal and rotary action of said circular plate means, and thereby causing said circular plate means to revolve it at intervals, and about the center of said stem means, and in this manner the relative movement of rotation is so arranged whereby the lateral distance of said scalloping cutting edges upon said plate will correspond to the feed of the cloth length as it may be fed by said feed bar member, including the

length of the stitch, while operating said sewing machine.

Another object of my invention is to provide said device with a pressure roller means which is revolvably mounted upon a suitable off center shaft means, said shaft means being adjustably and stationarily mounted within a suitable bracket means which is provided with a base member adapted for attaching and for bolting same upon the base of the sewing machine and thereby allowing the peripheral surface of said roller means to bear against said scalloping cutting edges of said plate means, so that the pinking of the cloth edges may be had while sewing same together during the operation of the sewing machine.

A further object of my invention is to provide said device with a circular plate means which is horizontally mounted upon a mounting plate, which is normally disposed upon the base and in close proximity to the feed and needle bars of the sewing machine and adapted for revolving about its center; the top section of said circular plate having scalloping cutting edges, which 20 in design or construction may be of any desired shape or configuration, wherever an adjustable roller means is disposed for causing its peripheral surface to bear upon and come in contact with said scalloping cutting edges, said roller means 25 having a shaft which is provided with an insulating bushing which is mounted within a suitable bracket member for holding said roller means in its proper position, having a suitable connector means attached to said shaft adapted for heating said roller means, so that in operation, when 30 said cloth is fed between said scalloping cutting edges and said peripheral surface of said roller means it will scorch the fiber of said cloth, thus 35 pinking the cloth edges while sewing same together during the operation of said machine.

Another object of my invention is to provide said device with a suitable circular plate means which is horizontally and revolvably mounted upon a mounting plate which is normally disposed upon the base of a sewing machine, having a suitable roller means adjustably and revolvably disposed over the surface of said circular plate means; the peripheral surface of said roller means being provided with suitably arranged 45 scalloping cutting edges which are adapted for contacting the surface of said circular plate means, and which also is provided with a shaft mounted within an insulated bushing means and disposed within a bracket member for holding 50 said roller means in place; said device having 55

suitable electrical connectors for transmitting the electrical current to said roller means and for heating said scalloping cutting edges, so that when the cloth or other material is fed thereunder and over said surface of said circular plate means, the fibers of said cloth are pressed and scorched, thus providing a pinking upon the cloth edges during the operation of the machine.

Other and further objects and advantages of my invention as will hereinafter more fully appear, I attain by the construction herein shown on the drawing and described in the specification forming a part of my application.

Reference is had to the accompanying drawing, in which the similar reference characters denote the similar parts.

In the drawing:

Fig. 1 is a perspective view of the sewing machine showing my invention mounted upon its base and in close proximity to the feed and needle bars.

Fig. 2 is an enlarged view of my invention showing the construction of the roller carrying bracket disposed in relation to and over the scalloping plate member, showing same mounted upon the base member of the sewing machine.

Fig. 3 shows a top view of the device disposed in relation to the feed bar member of the sewing machine, showing same in enlarged form.

Fig. 4 is a longitudinal sectional view of the device taken on the line 4—4 of Fig. 3.

Fig. 5 is a horizontal sectional view of the friction drive means, taken on the line 5—5 of the Fig. 4.

Fig. 6 is an elevational and sectional view of the device, showing same in a modified form.

Describing my invention more in detail, in its broader aspect, said invention comprises a circular plate 2 which is horizontally disposed upon a mounting plate 4, as shown in Fig. 3, and which is placed in close proximity to the feed bar member 6 and the needle passage 8.

Said circular plate 2 is provided at its top surface section 10 with a scalloping cutting edge 12 which is circularly disposed thereon and is raised off the surface for providing a sharp cutting edge, while at its underside a suitable stem member 20 is provided, the purpose of which will be presently described.

The mounting plate 4 is provided with a circular groove 14 wherein a plurality of frictionless ball-bearings 16 are placed and which are for the purpose of bearing against the under side 18 of said plate 2 and for supporting same while it is rotated about its center stem member 20.

Said stem member 20 is held in place within a locating bushing 22 which is located in said mounting plate 4, having its extended end 24 provided with a pair of flanges 26 between which flanges 26 the friction drive means 28 is positioned, comprising a collar member 30 having a set of angularly disposed grooves 32 which are adapted for receiving therein suitable rollers 34 and which are supported in place by means of extension springs 36, so as to permit said rollers 34 to bear against the surface 38, as shown in Fig. 5.

Said collar member 30 is provided with an extension lever 40 the end of which terminates with a suitable knob 42, the surface section of which is adapted for bearing against the rear section 44 of said feed bar member 6, and in addition said collar member 30 is provided with a suitable extension bar member 46 the end of which is equipped with a suitable spring 48 the end of

which is connected to the base member 50 of the sewing machine 52.

It may be noted that said spring 48 will have the tendency to hold said knob 42 of said extension lever 40 against the rear section 44 of said feed bar member 6, thus in operation, the reciprocal movement of said collar member 30 about its axis will cause said rollers 34 to engage said locating bushing 22, thus imposing a rotative movement to said circular plate 2, caused by said reciprocal movement of the feed bar member 6 during the operation of said sewing machine 52, and any adjustment of the stitch which is made for changing the reciprocal travel of said feed bar member 6, will cause said plate 2 to move in relation to the feed of the cloth or any other material which is fed thereby, while sewing the edges of said material together.

In order to cut the cloth edges by means of said scalloping edges 12, a suitable roller 54 is provided, comprising a pressure collar 56, the peripheral surface of which is adapted for bearing upon said cutting edges 12, and also having a frictionless radial bearing 58 which is mounted upon a stud 60 of the shaft member 62.

Said shaft member 62 is at off-center relation to said stud 60 and is mounted within a socket 64 of the bracket member 66 having its rear section 68 provided with a suitable locking member 70, while said bracket 66 is provided with a locating member 72, which is for the purpose of locating and holding said shaft member 62 in position, during the operation of the device.

For the purpose of mounting said bracket 66 upon the base member 50 of said sewing machine 52 its rear section 74 is provided with a base plate 76 which is undercut as at 78 for providing the clearance for said mounting plate 4, while said base plate 76 is equipped with suitable screws 80 for fastening same in place as shown in Figs. 3 and 4.

In operation said feed bar member 6 supported by the foot 82 of the foot lever 84 causes the cloth or other material to pass therebetween and simultaneously allows the needle of the needle-bar 86 to sew the cloth edges together by means of the thread 88, and also allows the extreme edges of said cloth to be fed in between the scalloping cutting edges 12 and the pressure collar 56, thus pinking said edges during the operation of the machine, and also allowing any changes of movement or of a stroke of said feed bar member 6 to change the circular movement of said plate 2 so that the sewing of said cloth edges and the pinking thereof are accomplished simultaneously and without interruption and any sideward pull of said cloth material during the operation of the apparatus is eliminated.

In Fig. 6 I have shown the apparatus in a modified form wherein the circular plate 2 is of similar construction as shown in Figs. 3 and 4, having a bracket member 66 as hereinbefore described.

It may be noted however that said plate 2 may be entirely flat at its outer surface 10' and that said pressure collar 56' at its surface 90 may be provided with suitably cut scalloping cutting edges 92.

Said pressure collar 56' may, if so desired, be provided with a suitable conduit rod 94 which extends through a hard rubber shaft member 62, and has its outwardly extending end 96 provided with a suitable terminal 98 to which an electric current carrying wire 100 is connected. The base plate 76 is provided with an insulating plate 102, which is also made out of hard rubber, for pre-

venting the electric current from passing into said base plate 50, having, however, a second terminal 104, connecting another lead wire 106, which carries the electric current into said circular plate 2 and thereby, by means of a contact, will cause said scalloping cutting edges 92 to become heated while the electric current passes therethrough.

Obviously, it may be noted that while said scalloping cutting edges 92 are heated and the cloth material passes thereunder and against the surface of said circular plate 2, the fibre structure of said cloth material will become scorched instantaneously, which will cause a fibre rupture and separation, thus leaving the edges cut in a zig-zag form and preventing the cloth fibre from raveling.

While I have thus described my invention with great particularity, it will be clear that the same may be modified throughout a wide range.

I accordingly do not propose to be limited to the exact details of construction herein shown on the drawing and described in the specification, but reserve the right in practice to make the necessary changes and the modifications therein, which may come within the scope of the appended claims.

I claim as my invention:

1. In a device of the class described comprising a mounting plate means, a circular plate means disposed over said mounting plate means, a stem means in said circular plate means extending downwardly therefrom, a locating bushing means disposed at said stem means, a collar means disposed around said locating bushing means, a plurality of frictionless ball bearings disposed between said locating bushing means and said collar means and at the under side of said circular plate means, a scalloping cutting edge means circularly disposed upon the top surface of said circular plate means, a pressure roller means disposed over and bearing against said cutting edges of said scalloping edge means, an extension lever connected to and extending out of said collar means having the extended end disposed at the rear section of the feed bar member and adapted for turning said circular plate means about its stem center and in relation to the reciprocal movement of the feed bar member of the sewing machine, a bar extending out of said collar means, and a spring connecting said bar and the base plate of said sewing machine for maintaining said extension lever against said feed bar member of said sewing machine.

2. In a device of the class described as disclosed in claim 1 the combination of, means for electrically heating said pressure roller means, and means for transmitting said electric current into said pressure roller means through said circular plate means, for scorching and cutting the fibre of the cloth passing therebetween during the operation of the machine.

5. 3. In a pinking device of the class described adapted to be used with a sewing machine, comprising, a mounting plate means mounted upon the base of said sewing machine, a circular plate means having its outer surface edge disposed in close proximity to the needle of said sewing machine, a row of frictionless bearing balls disposed between said mounting plate means and said circular plate means for reducing the surface friction therebetween, a stem in said circular plate means extending downwardly and through said mounting plate means, a scalloping means disposed upon said outer surface edge of said circular plate means, a bracket member mounted upon the base of said sewing machine and extending over said circular plate means, a roller means eccentrically and adjustably mounted at the extended end of said bracket member having its surface disposed over said scalloping means of said circular plate means, a friction driving means disposed at the underside of said mounting plate means and mounted upon said stem, a lever means extending out of said friction driving means, a knob means in said lever means for bearing against the feed member of said sewing machine thereby causing said friction driving means to engage said stem and revolve said circular plate means during the reciprocal action of said feed member, and resilient means connected to said friction driving means for holding said hub means in engaging position during the operation of said sewing machine.
10. 4. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
15. 5. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
20. 6. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
25. 7. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
30. 8. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
35. 9. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
40. 10. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
45. 11. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
50. 12. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
55. 13. In a pinking device of the class described adapted to be used with sewing machines, comprising, a mounting plate means disposed upon the base of said sewing machine, a circular plate means, a stem means in said circular plate means extending downwardly therefrom and through said mounting plate means, a bracket member mounted upon the base of said sewing machine and extending over said circular plate means, an off center shaft means adjustably mounted in said bracket member, a roller means revolvably mounted on said off center shaft means having its surface disposed adjustably over the outer edge surface of said circular plate means, a scalloping means upon the surface of said roller means, a friction driving means mounted upon said stem means of said circular plate means and disposed beneath said mounting plate means, a lever means extending out of said friction driving means and bearing against the feed bar member of said sewing machine for transmitting the reciprocal action of said feed bar member into a rotary action of said circular plate means, and resilient means connected to said friction driving means for holding said lever means in engaging position during the operation of said sewing machine.
